UNITED STATES PATENT OFFICE.

HARLEY E. ANDERSON, OF CHICAGO, ILLINOIS, ASSIGNOR, BY MESNE ASSIGNMENTS,
TO W. H. MINER, INC., A CORPORATION OF DELAWARE.

HAND BRAKE.

Application filed August 31, 1922. Serial No. 585,479.

To all whom it may concern:

Be it known that I, HARLEY E. ANDERSON, a citizen of the United States, residing at Chicago, in the county of Cook and State of Illinois, have invented a certain new and useful Improvement in Hand Brakes, of which the following is a full, clear, concise, and exact description, reference being had to the accompanying drawings, forming a part of this specification.

This invention relates to improvements in hand brakes.

One object of the invention is to provide a simple and efficient hand brake of the vertical staff type for railway cars wherein the brake is operated by a hand wheel, and means is provided for quickly releasing the brake upon reverse movement of the hand wheel for automatically disconnecting the chain pulling member from the brake staff upon turning the hand wheel in a direction to slacken the brake chain.

It is a further object of the invention to provide an automatic means to re-engage the chain pulling member with the brake staff when the brake has reached its fully released position.

Other objects of the invention will more fully appear from the description herein-after following.

In the drawings forming a part of this specification, Figure 1 is a vertical sectional view through a hand brake showing my improvements embodied therein and also showing in section the end portion of a car with the brake applied thereto. Fig. 2 is a horizontal sectional view on the line 2-2 of Fig. 1. And Fig. 3 is a side elevational view of the traveling block, looking from the left of Fig. 1.

In said drawing, 10 denotes the end sill of a railway car, 11 the end post and 12 the end wall or outer sheathing.

My improved brake, as shown, comprises, 45 a housing A; a brake staff B; a worm C; a traveling block D; and a brake chain E.

As shown, the housing A comprises vertically extending front wall 13, side walls 14-14 and a broken rear wall comprising 50 the upwardly and downwardly extending portions 15 and 16. Projecting horizontally in a rearward direction from the wall 15, is a lug 17 for securing the housing to the end sill 10. The lug 17 is perforated at 18 to receive a lag screw 19 for supporting the hous-

ing. The wall 16 is provided with oppositely extending lugs 20 and 21, suitably perforated to receive the lag screws 22, by means of which the upper end of the housing is secured to the end wall 12 and the post 11. The bottom 23 of the housing is perforated at 24 to receive the brake chain E and is provided with downwardly extending spaced bearing lugs 25 to support the grooved idler pulley 26, the lugs being 65 perforated to receive the transverse shaft 27 upon which the pulley 26 is journaled. The bottom 23 of the housing A is also perforated at 28 to receive the lower end of the brake staff B and form a journal therefor. 70 Around the perforation 28, the bottom 23 is provided with an upwardly extending circular flange 29 which forms an abutment for the lower end of the worm C. The upper wall 30 of the casing A is perforated at 75 31 to form a bearing opening to receive the upper end of the worm C. The opening 31 of the upper wall 30 is surrounded by a vertically extending circular flange 32.

The brake staff B has the portion thereof 80 within the worm formed square, as shown in Fig. 2, and is provided with a cylindrical lower end portion 33 journaled in the opening 28, and an upper cylindrical portion 34. The hand wheel 35 is secured to 85 the upper end of the brake staff B by the upper end of the brake staff being formed square and the hand wheel 35 having a correspondingly square recess fitting thereon, or secured in any other well known 90 manner.

The worm C is of cylindrical form and has its exterior cylindrical surface provided with heavy threads 36. The upper end of the worm C is provided with a smooth cylindrical portion 37 journaled within the recess 31. The cylindrical portion 37 is provided with a laterally extending circular flange 38 having a down-turned outer edge portion 39, thereby providing a circular recess 40 adapted to receive the flange 32 projecting from the upper wall of the housing A. The worm C is also provided with a longitudinally extending bore of square cross section as indicated at 41 in Fig. 2, to 100 snugly receive the squared portion of the brake staff B so that the worm will be rotated therewith. The lower end 42 of the worm rests upon the upper face of the flange 29 and the circular flange 38 at the upper 110

end of the worm is supported upon the upwardly projecting flange 32 on the upper wall 30 of the housing A. The lower end of the brake staff B is adapted to receive a 5 cotter-pin 43 whereby the brake staff and worm are held in assembled relation with the housing A.

The chain carrying block D, as best shown in Figs. 1 and 3, is provided with part 10 threads 44 on one of its faces, adapted to co-act with the threads 36 of the worm C. The wall of the chain carrying block D opposite to the threaded portion 44 is provided with two recesses 45 and 46 adapted to receive cam members 47 and 48. As shown, the recess 45 is open at its top and side so as to allow a rocking movement of the cam 47, and the recess 46 is of a sufficient height to allow the outer end of the cam 48 to pass 15 within the same when the cam is rocked upwardly relatively to the block. The cams 47 and 48 are pivotally supported within the recesses 45 and 46 by the pivot pins 49 and 50. The lower end of the chain carrying block D is provided with downwardly projecting spaced lugs 51 providing means for attaching the chain to the block, the last link of the chain being secured to the lugs 51 by transversely extending pin 52 passing 20 through said link.

The cams 47 and 48, as shown, have their 25 pivotal openings eccentrically located so as to dispose their centers of weight eccentric to the pivot pins to allow them to be returned to their lowermost position by the force of gravity. The cams 47 and 48 are provided with curved cam faces 53 and 54 adapted to co-act with the inner face 55 of the front wall 13 of the housing A and the 30 distance between the pivot pins 49 and 50 and the high points of the cam faces 53 and 54 is such that when the high points of the cam faces 53 and 54 are in engagement with the inner face 55 of the front 35 wall 13 of the housing A, the threads 44 on the block D will be held in engagement with the threads 36 of the worm C. It will thus be clear that the threads will be held in engagement at all times when the 40 cams 47 and 48 are in their lowermost positions with the high points engaging the inner face of the front wall of the casing.

The lower end of the housing A, is provided with interior downwardly extending 45 inclined ribs 56 located at opposite sides of the same and spaced apart as shown in Fig. 2, to provide a space within which is loosely received the lower cam 48 when the block is in its lowermost position. The 50 lower portion of the block D is provided with inclined faces 57 which co-act with the inclined ribs 56 to move the block D inwardly toward the staff when the block reaches its lowermost position in the casing.

In the operation of my improved hand 65 brake, the hand wheel 35 is turned in a clockwise direction, looking down vertically in Fig. 1, to tighten the brakes. In rotating the hand wheel 35 in a clockwise direction, the worm C will be rotated therewith in the same direction and the block D will be moved in an upward direction by the threads 36 co-acting with the threads 44 on the block. During this upward 70 movement of the block, the cams 47 and 48 will be held in their lowermost position as shown in Fig. 1 in full lines, due to the force of gravity and due to the frictional contact with the inner wall 55 of the housing A, thereby holding the threads on the block D constantly in engagement with the threads 37 on the worm. The rotation of the brake staff and worm C is continued until the block D has been moved upwardly 75 a sufficient distance to properly tighten the 80 brake through the action of the chain E. The position of the block when the brake has been tightly set will generally be near the upper end of the casing A and the 85 approximate position of the same is shown in dotted lines in Fig. 1. It is, of course, obvious that the block need not be raised to the height shown by the dotted lines in Fig. 1 to tighten the brake properly, but may reach some intermediate position, 90 dependent upon the amount of slack originally in the brake chain.

In releasing the brake, hand wheel 35 is turned in the opposite direction to that 95 previously described, thus rotating the 100 worm C in the opposite direction also, thereby causing inter-engaging threads 36 and 44 to move the block D downwardly. As the block D is moved downwardly in the casing A, the cams 47 and 48 being 105 in frictional contact with the side wall 13 of the housing A will be rocked upwardly relatively to the block and the cam faces 53-54 moved inwardly toward the block, thus allowing the block to be pulled outwardly toward the wall 13 of the casing A under the tension of the chain and permitting disengagement of the threads 36 and 44. It will thus be seen that the block 110 is free to swing outwardly and entirely 115 clear the threads 36 of the worm C so as to completely release the block and allow the same to drop to the bottom of the casing A, where the faces 57 on the block 120 will engage with the inclined ribs 56 on the front wall of the casing and then automatically guide the block inwardly and re-engage the threads 44 with the threads 36 of the worm C. As the block D is moved laterally toward the brake staff by the camming action of the inclines 56 and 57, the 125 cams 47 and 48 will be allowed to rock, by the force of gravity, on their pivots 49.

and 50 and swing to their lowermost position with the high parts 53—54 the cam faces in engagement with the inner face 55 of the wall 13 of the housing A.

5 From the foregoing, it will be seen that means is provided for quickly releasing the brake chain carrying block, upon reverse rotary movement of the brake staff B, and re-engaging the block with the staff 10 upon reaching the bottom of the casing, when the block and other parts are again in position so that the same may be operated to properly tighten the brakes.

I have herein shown and described what 15 I now consider the preferred manner of carrying out my invention, but the same is merely illustrative and I contemplate all changes and modifications that come within the scope of the claims appended 20 hereto.

I claim:

1. In a hand brake for railway cars; the combination with a shaft; of a brake chain; mechanism connecting the shaft and chain 25 to cause the chain to be tightened during the rotation of said shaft in one direction; and automatic means for causing said mechanism to be disconnected upon rotation of said shaft in the reverse direction.

30 2. In a hand brake for railway cars; the combination with a brake staff; of a brake chain; mechanism connecting the staff and chain to cause the chain to be tightened during the rotation of said staff in one direction; 35 automatic means for causing said mechanism to be disconnected upon rotation of said staff in the reverse direction; and automatic means for causing said mechanism to be again connected upon release of the brake.

40 3. In a hand brake for railway cars; the combination with a brake staff said staff being rotatable in one direction to tighten the brakes; of a brake chain tightening means; and means arranged to be set in operation by rotation of said staff in a reverse direction, for disconnecting said tightening means to cause a release of the brakes.

45 4. In a hand brake for railway cars; the combination with a brake staff; of a brake-chain tightening means; means arranged to be set in operation by said staff, for disconnecting said tightening means to cause a release of the brakes; and automatic means to cause said tightening means to be again 55 connected.

50 5. In a hand brake for railway cars; the combination with a traveling member having a brake chain connected thereto; of means for causing said member to travel in a direction to tighten the brake chain and also in a direction to slacken the same; and mechanism controlled by said means, for causing said member to be disconnected from said first named means upon operation of 60 said first named means to cause said member

to travel in a direction to slacken the chain.

6. In a hand brake for railway cars; the combination with a traveling member having a brake chain connected thereto; of means for causing said member to travel in 70 a direction to tighten the brake chain and also in a direction to slacken the same; mechanism controlled by said means for causing said member to be disconnected from said first named means upon operation of 75 said first named means to cause said member to travel in a direction to slacken the chain; and means for re-engaging said first named means and said member.

7. In a hand brake for railway cars; the 80 combination with a traveling member having a brake chain connected thereto; of means for causing said member to travel, to tighten and slacken the chain; and devices controlled by the travel of said member for 85 causing the same to be disconnected from said first named means.

8. In a hand brake for railway cars; the combination with a traveling member having a brake chain connected thereto; of 90 means for causing said member to travel in one direction, to tighten and in the opposite direction to slacken the chain; devices controlled by the operation of said means in effecting movement of said member in the direction last named for causing said member to be disconnected from said means; and means for re-engaging said member and said first named means.

9. In a hand brake for railway cars; the 100 combination with a brake staff; of a traveling member having a brake chain connected thereto; cooperating means on said staff and member for causing said member to travel upon operation of said staff; and devices 105 controlled by the movement of said member for causing said means to be disconnected.

10. In a hand brake for railway cars; the combination with a brake staff; of a traveling member having a brake chain connected 110 thereto; cooperating means on said staff and member for causing said member to travel upon operation of said staff; devices controlled by the movement of said member for causing said means to be disconnected; and 115 automatic means for again connecting said means.

11. In a hand brake for railway cars, the combination with a rotary brake staff; of a traveling member having a brake chain connected thereto; co-operating means on said staff and said member for causing said member to travel in a chain tightening direction when said staff is rotated in one direction and for causing said member to travel in a 120 reverse direction upon rotation of said staff in the opposite direction; and means operated by the movement of said member in said reverse direction to cause the first named means to be disconnected.

12. In a hand brake for railway cars, the combination with a rotary brake staff; of a traveling member having a brake chain connected thereto; co-operating means on said staff and said member for causing said member to travel in a chain tightening direction when said staff is rotated in one direction and for causing said member to travel in a reverse direction upon rotation of said staff in the opposite direction; means operated by the movement of said member in said reverse direction to cause the first named means to be disconnected; and means for again connecting said first named means.

13. In a hand brake for railway cars; the combination with a rotary brake staff having a worm thereon; of a traveling member having a brake chain connected thereto, said member having a sectional threaded portion co-acting with said worm to cause the member to travel upon rotation of said staff, said member also being adapted for movement laterally to disengage the threaded portion and worm; and means for normally holding said member in engagement with said worm, said means being operated upon rotation of said staff in a direction to release the brakes to allow lateral movement of said member to disengage the threaded portion and the worm.

14. In a hand brake for railway cars; the combination with a rotary brake staff having a worm thereon; of a traveling member having a brake chain connected thereto, said member having a sectional threaded portion co-acting with said worm to cause the member to travel upon rotation of said staff, said member also being adapted for movement laterally to disengage the threaded portion and worm; means for normally holding said member in engagement with said worm, said means being operated upon rotation of said staff in a direction to release the brakes to allow lateral movement of said member to disengage the threaded portion and the worm; and means for causing the member to move laterally to re-engage the threaded portion with the worm.

15. In a hand brake for railway cars; the combination with a rotary brake staff having a worm thereon; of a traveling member having a brake chain connected thereto, said member having a sectionally threaded portion co-acting with said worm to cause the member to travel upon rotation of said staff, said member also being adapted for movement laterally to disengage the threaded portion and worm; and gravity actuated

means for normally holding said member in engagement with said worm, said means being operated upon rotation of said staff in a direction to release the brakes to allow lateral movement of said member to disengage the threaded portion and the worm.

16. In a hand brake, the combination with a rotary brake staff having a worm thereon; of a housing enclosing said worm and having a front wall provided with a cam on its inner face; a traveling member within said housing, said member having a brake chain attached thereto and provided with a sectional threaded portion co-acting with said worm to cause said member to travel when the staff is rotated; a cam portion adapted to co-act with said first named cam to cause said threaded portion and worm to engage; gravity operated pivoted cams mounted on said member and engaging said wall to normally hold the member spaced from the wall and in engagement with said worm, said gravity operated cams being adapted to be rocked by frictional contact with said wall upon movement of said member in a direction to release the brakes, to thereby allow said member to move laterally toward the wall and away from the worm to cause disengagement of said worm and threaded portion.

17. In a hand brake, the combination with a rotary brake staff having a worm thereon; of a housing enclosing said worm and provided with a cam; a traveling member within said housing, said member having a brake chain attached thereto and provided with a sectional threaded portion co-acting with said worm to cause said member to travel when the staff is rotated; a cam portion adapted to co-act with said first named cam to cause said threaded portion and worm to engage; gravity operated pivoted cams mounted on said member to normally hold the same in engagement with said worm, said gravity operated cams being adapted to be rocked by frictional contact with said housing upon movement of said member in a direction to release the brakes to thereby allow said member to move laterally to cause disengagement of said worm and threaded portion.

In witness that I claim the foregoing I have hereunto subscribed my name this 14th day of August 1922.

HARLEY E. ANDERSON.
